(57) **CLAIM**

The ornamental design for a cartomizer, as shown and described.

DESCRIPTION

FIG. 1 is a front perspective view of a cartomizer showing our new design;

FIG. 2 is a rear perspective view thereof;

FIG. 3 is a front elevational view thereof;

FIG. 4 is a rear elevational view thereof;

FIG. 5 is a side elevational view thereof;

FIG. 6 is a top plan view thereof; and,

FIG. 7 is a bottom plan view thereof.

The dash-dash broken lines illustrate portions of the cartomizer that form no part of the claimed design.

The dash-dot lines illustrate boundary lines that form no part of the claimed design. The areas within the dash-dot lines form no part of the claimed design.

1 Claim, 6 Drawing Sheets
